ABSTRACT

A retractable canopy for a watercraft lift comprising an actuator operatively connected to the watercraft lift and a movable boom to rotate the movable boom relative to the watercraft lift; a linkage extends between the fixed boom and the movable boom, at least one first strut is supported by the linkage, at least one second strut is supported by a fixed boom; and at least one third strut is supported by the movable boom. The fixed boom, the movable boom, the at least one second strut, and the at least one third strut support a cover in an extended configuration above a watercraft area. The fixed boom, the movable boom, the at least one first strut, the at least one second strut, and the at least one third strut support the cover in a retracted configuration adjacent to the fixed strut.

BACKGROUND

Technical Field

The present disclosure pertains to deployable coverings for objects and, more particularly, to canopy devices, systems, and methods, that enable selectable degrees of deployment and provide a fully folded configuration useful with vehicles and in connection with boat lifts.

Description of the Related Art

Canopies for objects, such as vehicles, are known. Typical canopies include a frame and a cover to provide a protected space under which to store an object or park a vehicle. The canopy frame typically extends vertically and horizontally to span an area such that when an object is placed under the canopy, the cover provides protection for the object from the sun, rain, or snow, among other environmental conditions. However, fixed or permanent canopies suffer from a number of drawbacks or disadvantages.

For example, the permanent shade created by fixed canopies is frowned upon in many jurisdictions because of the negative impact to surrounding ecosystems. Further, permanent canopies are not aesthetically pleasing and are typically viewed negatively by homeowners or neighbors. These problems are exacerbated when fixed canopies block waterfront views, or other scenic landscape views. Moreover, designing canopy covers and frames to handle snow and wind loads requires use of expensive and bulky parts, which increases cost for the consumer. Because fixed canopies are suspended above an area, most fixed canopies also do not provide adequate protection against environmental conditions impinging on the object or vehicle underneath the canopy from different angles, such as from the side. Such canopies are also not adjustable, meaning that the area

covered by the canopy is fixed based on the size and arrangement of the frame, which limits use applications.

Some of the above issues are alleviated with removable canopy covers, but such canopy covers are typically formed from heavy material and are burdensome or cumbersome for the owner to manipulate on and off of the frame. Other solutions include covers that extend laterally toward the support surface to provide protection to the sides of an object under the canopy, but such solutions do not address the environmental or aesthetic concerns mentioned above and are also not adjustable. As such, current canopies suffer from a number of disadvantages, as do available proposed solutions.

15

BRIEF SUMMARY

A first implementation of a retractable canopy for a watercraft lift may be summarized as including: a fixed boom extending from the watercraft lift; a movable boom supported for rotational movement by the watercraft lift; an actuator operatively connected to the watercraft lift and the movable boom to rotate the movable boom between first and second positions relative to the watercraft lift, wherein the movable boom is spaced from the fixed boom when in the first position and is adjacent to the fixed boom when in the second position; at least one first linkage extending between the fixed boom and the movable boom; at least one second linkage extending between the fixed boom and the movable boom; at least one first strut rotatably supported by the at least one first linkage and slidably supported by the at least one second linkage; at least one second strut supported by the fixed boom; at least one third strut supported by the movable boom; and a cover secured at a first end to the fixed boom and at a second end to the movable boom; whereby when the movable boom is in the first position, the fixed boom, the movable boom, the at least one first strut, the at least one second strut, and the at least one third strut support the cover in an extended configuration above a watercraft area; and when the movable boom is in the second position, the fixed boom, the movable boom, the at least one first strut, the at least one second strut, and the at least one third strut support the cover in a retracted configuration adjacent to the fixed strut.

FIGS. 28A-28F are side elevation views of the eleventh implementation of the support structure of FIGS. 26A-26F.

DETAILED DESCRIPTION

FIGS. 1A-1K and 2A-2K depict the operation of a first example support structure for a retractable canopy for boats. A canopy member (not shown), typically a flexible sheet of weather resistant of flexible material, is supported by the support structure over the boat when the support structure is in the fully open. When the support structure is fully retracted, the canopy member is folded.

FIGS. 3A-3K and 4A-4K depict the operation of a second example support structure for a retractable canopy for boats. A canopy member (not shown), typically a flexible sheet of weather resistant material, is supported by the support structure over the boat when the support structure is in the fully open. When the support structure is fully retracted, the canopy member is rolled up within a roller assembly.

FIGS. 5A-5K and 6A-6K depict the operation of a third example support structure for a retractable canopy for boats. A canopy member (not shown), typically a flexible sheet of weather resistant material, is supported by the support structure over the boat when the support structure is in the fully open. When the support structure is fully retracted, the canopy member is rolled up within a roller assembly.

FIGS. 7A-7K and 8A-8K depict the operation of a fourth example support structure for a retractable canopy for boats.

10 A canopy member (not shown), typically a flexible sheet of weather resistant material, is supported by the support structure over the boat when the support structure is in the fully open. When the support structure is fully retracted, the canopy member is rolled up within a roller assembly.

15 FIGS. 9 and 10A-10H depict the operation of a fifth example support structure for a retractable canopy for boats. A canopy member (not shown), typically a flexible sheet of weather resistant of flexible material, is supported by the support structure over the boat when the support structure is in the fully open. When the support structure is fully retracted, the canopy member is folded.

FIGS. 11A-11K, 12A-12K, and 13A-13K depict the operation of a sixth example support structure for a retractable canopy for boats. A canopy member (not shown), typically a flexible sheet of weather resistant of flexible material, is supported by the support structure over the boat when the support structure is in the fully open. When the support structure is fully retracted, the canopy member is folded.

20 FIGS. 14A-14P, 15A-15P, and 16A-16P depict the operation of a seventh example support structure for a retractable canopy for boats. A canopy member (not shown), typically a flexible sheet of weather resistant of flexible material, is supported by the support structure over the boat when the support structure is in the fully open. When the support structure is fully retracted, the canopy member is folded.

25 FIGS. 17A-17I and 18A-18I depict the operation of an eight example support structure for a retractable canopy for boats. A canopy member (not shown), typically a flexible sheet of weather resistant of flexible material, is supported by the support structure over the boat when the support structure is in the fully open. When the support structure is fully retracted, the canopy member is folded. FIGS. 17A-17I and 18A-18I also illustrate that any one of the example 30 retractable canopy systems for boats depicted above can be used with a boat lift system such as the example boat lift system depicted therein.

FIGS. 19A-19E, 20A-20E, 21A-21E, and 22A-22E depict the operation of a ninth example support structure for a retractable canopy for boats of the present disclosure as used in connection with an example boat lift system, with the canopy removed in FIGS. 19A-19E and 22A-22E for clarity.

FIGS. 23A-23D, 24A-24D, and 25A-25D depict the operation of a tenth example support structure for a retractable canopy for boats of the present disclosure as used in connection with an example boat lift system. A canopy member, typically a flexible sheet of weather resistant flexible material, is supported by the support structure over the boat when the support structure is fully open. When the support structure is fully retracted, the canopy member is folded.

FIGS. 23A-23D are perspective views of an implementation of a retractable canopy 20 for a watercraft lift 22. The retractable canopy 20 includes a fixed boom 24 extending 55 from the watercraft lift 22. A movable boom 26 is supported for rotational movement by the watercraft lift 22. An actuator 28 (shown in FIG. 23C) is operatively connected to the

watercraft lift 22 and the movable boom 26 to rotate the movable boom 26 between a first position as in FIG. 1A and a second position as in FIG. 1B relative to the watercraft lift 22. In the first position shown in FIG. 1A, the movable boom 26 is spaced from the fixed boom 24. In the second position, the movable boom 26 is adjacent to the fixed boom 24.

The retractable canopy 20 further includes at least one first linkage 30 extending between the fixed boom 24 and the movable boom 26 and at least one second linkage 32 extending between the fixed boom 24 and the movable boom 26. At least one first strut 34 is rotatably supported by the at least one first linkage 30 and slidably supported by the at least one second linkage 32, as further described herein. In one implementation, the retractable canopy 20 includes at least one second strut 36 rotatable relative to the fixed boom 24 and at least one third strut 38 supported by the movable boom 26. A cover 40 is secured at a first end 42 to the fixed boom 24 and at a second end 44 to the movable boom 26.

When the movable boom 26 is in the first position, the fixed boom 24, the movable boom 26, the at least one first strut 34, the at least one second strut 36, and the at least one third strut 38 support the cover 40 in an extended configuration above a watercraft area (e.g. area of boat 46) as shown in FIG. 1A. When the movable boom 26 is in the second position, the fixed boom 24, the movable boom 26, the at least one first strut 34, the at least one second strut 36, and the at least one third strut 38 support the cover 40 in a retracted configuration adjacent to the fixed strut 24, as shown in FIG. 1D.

In one implementation, the retractable canopy 20 further includes a support post 48 coupled to the watercraft lift 22, wherein when the movable boom 26 is in the first position, the movable boom 26 contacts the support post 48, as best shown in FIG. 1A. Further, the retractable canopy 20 includes a support rod 50 coupled between one of the at least one third struts 38 and one of the at least one first linkages 30. Preferably, the at least one first strut 34 is also rotatably supported by the at least one second linkage 32. In yet a further implementation, each of the at least one first linkage 30 and each of the at least one second linkage 32 include a first portion 52 coupled to the fixed boom 24 and structured to rotate relative to the fixed boom 24 and a second portion 54 coupled to the movable boom 26 and structured to rotate relative to the movable boom, the first portion 52 coupled to the second portion 54, wherein the first portion 52 and the second portion 54 are structured to rotate relative to each other.

Finally, FIGS. 26A-26F, 27A-27F, and 28A-28F depict the operation of an eleventh example support structure for a retractable canopy for boats of the present disclosure as used in connection with an example boat lift system.

In general, in the following claims, the terms used should not be construed to limit the claims to the specific embodiments disclosed in the specification and the claims, but should be construed to include all possible embodiments along with the full scope of equivalents to which such claims are entitled. Accordingly, the claims are not limited by the disclosure.

What is claimed is:

1. A retractable canopy for a watercraft lift comprising: a fixed boom extending from the watercraft lift; a movable boom supported for rotational movement by the watercraft lift; an actuator operatively connected to the watercraft lift and the movable boom to rotate the movable boom between first and second positions relative to the watercraft lift, where the movable boom is spaced from the fixed

boom when in the first position and is adjacent to the fixed boom when in the second position;

at least one first linkage extending between the fixed boom and the movable boom;

at least one second linkage extending between the fixed boom and the movable boom;

at least one first strut rotatably supported by the at least one first linkage and slidably supported by the at least one second linkage;

at least one second strut supported by the fixed boom;

at least one third strut supported by the movable boom; and

a cover secured at a first end to the fixed boom and at a second end to the movable boom; whereby

when the movable boom is in the first position, the fixed boom, the movable boom, the at least one first strut, the at least one second strut, and the at least one third strut support the cover in an extended configuration above a watercraft area; and

when the movable boom is in the second position, the fixed boom, the movable boom, the at least one first strut, the at least one second strut, and the at least one third strut support the cover in a retracted configuration adjacent to the fixed strut.

2. The retractable canopy of claim 1 wherein the at least one first linkage includes two first linkages on opposite sides of the fixed boom and the movable boom.

3. The retractable canopy of claim 2 wherein the at least one second linkage includes two second linkages on opposite sides of the fixed boom and the movable boom, the second linkages spaced from the first linkages.

4. The retractable canopy of claim 1 further comprising: a support post coupled to the watercraft lift and configured to limit rotational motion of the movable boom.

5. A retractable canopy comprising:
a fixed boom;
a movable boom coupled to the fixed boom and structured to rotate relative to the fixed boom;
an actuator coupled to the fixed boom and the movable boom and structured to rotate the movable boom;
a first linkage coupled to the fixed boom and the movable boom and structured to rotate relative to the fixed boom and movable boom;
a second linkage coupled to the fixed boom and the movable boom and structured to rotate relative to the fixed boom and the movable boom; and
a first strut coupled to the first linkage and the second linkage and structured to rotate relative to the first linkage and the second linkage, the first strut further structured to slide relative to the second linkage.

6. The retractable canopy of claim 5 wherein the actuator is structured to rotate the movable boom between a first position and a second position relative to the fixed boom, wherein the movable boom is spaced from the fixed boom in the first position and the movable boom is proximate the fixed boom in the second position.

7. The retractable canopy of claim 6 further comprising: a second strut coupled to the fixed boom, the second strut structured to rotate relative to the fixed boom.

8. The retractable canopy of claim 7 further comprising: a third strut coupled to the movable boom, the third strut structured to rotate relative to the fixed boom.

9. The retractable canopy of claim 8 further comprising: a cover having a first end and a second end, the first end coupled to the fixed boom and the second end coupled to the movable boom,

wherein the fixed boom, the movable boom, the first strut, the second strut, and third strut are structured to support the cover in an extended configuration above a water-craft area corresponding to the movable boom being in the first position; and

5

wherein the fixed boom, the movable boom, the first strut, the second strut, and the third strut support the cover in a retracted configuration adjacent to the fixed boom corresponding to the movable boom being in the second position.

10

10. The retractable canopy of claim 5 further comprising: a cover having a first end and a second end, the first end coupled to the fixed boom and the second end coupled to the movable boom, wherein the fixed boom, the movable boom, and the first strut are structured to support the cover in an extend configuration corresponding to the movable boom being in the first position.
